OR D 2,291 EX

Design for A Clock Base.

Fig. 2,291.

By William A. Giles.

Patented April 3, 1866 Chicago Ill.

DES. 2291

William A. Giles of Chicago Ill.
Letters Patent No. 2291 Dated April 3. 1866.

Design for a Clock Case.

The schedule referred to in the Letters Patent and making part of the same.

To all whom it may concern:

Be it known that I, William A. Giles, of the City of Chicago in the County of Cook and State of Illinois have invented or produced a new and original design for a Clock Case and I do hereby declare that the following is a full and exact description of the same.

The peculiar form of this Clock will be perceived and understood from an inspection of the drawing. Its general shape is that of an oblong, standing on its small end, on short curved legs and having its upper end or side rounded into a half circle. The whole outline however is very irregular being formed of stalks of Indian corn on each side, the butts of which project below the rest of the frame thereby forming the legs, and the tops being intertwined or twisted together so as to form a half circle as already shown. On the stalks there are ears of corn, more or less covered by the husks, and there are also many leaves some standing upright or nearly so, and some broken or bent down.

In the centre of the upper half of the front of this case is the face of the clock in the ordinary form. In the centre of the lower half and directly beneath the real face is a false face of the same size as the upper, but without any figures or hands.

The whole thus forms a rustic Clock Case, intended to be carved out of black walnut or any other wood suitable for the purpose, and with stalks and leaves and

2

Oct. 2291

end of corn for the border instead of black walnut or other wood, bronze or other metal may be employed if desired.

Having thus described my design what I claim as my invention or production and desire to secure by Letters Patent is The design for a rustic clock base substantially as shown and described

Witness.
